APPARATUS FOR SEALING CONTAINERS

Harry E. Stover, Leonia, N. J., assignor to Anchor-Hocking Glass Corporation, Lancaster, Ohio, a corporation of Delaware

Original application February 16, 1940, Serial No. 319,312. Divided and this application June 6, 1941, Serial No. 396,887.

3 Claims. (Cl. 226—88.1)

My invention relates to cap-feeding apparatus. It has to do, more particularly, with apparatus for feeding caps from a source of supply and applying them to containers, such as food containers and including jars, bottles, cans, et cetera, preparatory to sealing them on said containers.

One of the objects of my invention is to provide a simple and effective apparatus for feeding caps from a source of supply into position to be engaged by the upper ends of containers to be sealed thereby which are moved along by a conveyor.

Another object of my invention is to provide apparatus which will automatically release caps from a cap magazine and feed them into position to be engaged by the top of the containers without any manual intervention by the operator.

Another object of my invention is to provide a cap-feeding and applying unit of such a nature that the cap can be withdrawn therefrom by a container on a moving conveyor without danger of upsetting the container.

Another object of my invention is to provide a cap-feeding apparatus of such a nature that the cap which is fed into position to be engaged by a container will not drop from the cap-feeding mechanism until it is positively withdrawn by a passing container.

Another object of my invention is to provide a cap-feeding unit having a magazine for a vertically disposed stack of caps and which is of such a nature that the lowermost cap will be separated from the stack while the stack is supported in position.

Another object of my invention is to provide a cap-feeding apparatus including a magazine and cap-feeding unit which can be removed and replaced readily when different size caps are to be used.

In its preferred form, my invention contemplates the provision of a simple apparatus for feeding caps from a source of supply and applying them to containers such as jars, bottles, cans, et cetera. The apparatus is preferably employed with a continuously moving conveyor upon which the filled containers are placed indiscriminately. Means is preferably provided in association with the conveyor for centering and maintaining the containers centered on said conveyor. The containers are first moved by the conveyor to my cap-feeding and applying unit where caps or other closures are loosely positioned on the upper ends of the containers. The containers may then be moved to a sealing unit such as is described in my parent application, Serial No. 319,312. It will, of

course, be understood that any suitable sealing unit may be used in conjunction with my cap-feeding apparatus. The sealing head and my cap-feeding and applying unit are preferably separately disposed directly adjacent each other. My cap-feeding and applying unit is preferably connected to the sealing head so that each time the sealing head is actuated, a cap is fed from my cap-feeding unit into position to be engaged by the next container in the conveyor. It is not, however, necessary to operate the cap-feeding and applying unit by the sealing head.

This application is a division of my co-pending application Serial No. 319,312, filed February 16, 1940, which issued as Patent Number 2,309,548.

Various other objects and advantages will be apparent from the following description.

The preferred embodiment of my invention is illustrated in the accompanying drawings, wherein similar characters of reference designate corresponding parts and wherein:

Figure 1 is a plan view of my cap-feeding and applying apparatus showing it associated with a sealing machine.

Figure 2 is a side elevational view of the apparatus shown in Figure 1.

Figure 3 is a vertical sectional view taken through the cap-feeding unit showing one cap in position to be engaged by a container.

Figure 4 is a perspective view showing a separating wedge of the cap-feeding unit.

Figure 5 is a view partly in horizontal section and partly in plan taken substantially along line 5—5 of Figure 6.

Figure 6 is a vertical sectional view taken substantially along line 6—6 of Figure 5.

Figure 7 is a view partly in side elevation and partly in section taken substantially along line 7—7 of Figure 5.

With reference to the drawings, I have illustrated a machine which comprises generally a conveyor unit 1, a cap-feeding and applying unit 2 and a sealing head unit 3.

The conveyor unit 1 may be of any suitable type. For example, it may be of the type disclosed in the co-pending application of William D. Bell on Apparatus for sealing containers, Serial No. 314,299, filed January 17, 1940. However, it is to be understood that my apparatus may be associated with any suitable type of conveyor unit. The conveyor unit preferably embodies means for continuously moving the containers into proper association with the units 2 and 3, including means for centering the containers relative to said units.

My invention is not limited to use with any particular type of container and cooperating cap but for illustrative purposes I have shown in Figure 3 a tumbler 4 adapted to receive the cap 5 on its upper end. This cap preferably embodies a substantially disk-like portion which has a depending annular skirt.

The containers 4 are placed indiscriminately on the conveyer and are moved in the direction of the arrows (Figures 1 and 2) by the conveyer. The containers are centered thereon in the manner described in said co-pending application Serial No. 319,312. They are first carried to the cap-feeding and applying unit 2. This unit is of such a type that it will apply a cap loosely to the upper end of the container. After the container passes the unit 2, it passes to the sealing head unit 3. This sealing head unit 3 is adapted to displace the air from the head space and to sterilize such space and the cap before the sealing operation.

The units 2 and 3 are disposed directly adjacent each other. They are both supported by a horizontally disposed plate 9. The plate 9 is supported at a point spaced above the conveyer unit 1 by means of four vertically disposed non-rotatable posts 10 which are disposed at each corner of the plate. Each of these posts 10 is provided with a base portion 11 on its lower end which is suitably secured, as by screw bolts 11a, to a portion of the conveyer unit 1. The upper portion of each of these posts is threaded, as indicated at 12. Each of the posts has an internally threaded worm gear 13 mounted on the threaded portion 12 thereof. Each of these worm gears is disposed directly beneath and engages a corner extension 14 of the plate 9. Bolted to the side of each of these corner extensions 14 is a bracket 15. The pair of brackets 15 at the right hand end of the plate 9 (Figure 1) rotatably support a horizontally disposed worm shaft 16. The pair of brackets 15 at the other end of the plate 9 rotatably support a horizontally disposed worm shaft 17. Each of the worm shafts 16 and 17 carries a pair of worms 18 which engage the adjacent worm gears 13. The worm shaft 17 is provided with an angular end 19 for receiving a crank by means of which it may be rotated. In order to rotate the shaft 16 simultaneously with the shaft 17, the shaft 17 is provided on its opposite end with a sprocket 20 keyed thereon. This sprocket has a chain 21 passing therearound which also passes around a sprocket 22 keyed on the corresponding end of the shaft 16.

Thus, it will be apparent that when the shaft 17 is rotated, the shaft 16 will be rotated simultaneously and to the same extent. Consequently, by rotating shaft 17, all of the worm gears 13 will be caused to rotate. Since these gears are threaded on the posts 10, they will be moved vertically on the posts. Furthermore, since the gears are in engagement with lower surfaces of the plate 9, the plate 9 will be moved vertically in accordance with the vertical movement of the gears. Thus, the plate 9 may be adjusted vertically to position the units 2 and 3 at the proper height above the conveyer unit, depending upon the height of the containers to be sealed. It will be noted that all portions of my apparatus are carried by the plate 9. Consequently, it is in the form of a unitary structure which may be readily associated with any suitable type of conveyer unit.

The sealing head unit 3 is illustrated gener-

ally in Figures 1 and 2, and is described in detail in my co-pending application Serial No. 319,312. It comprises a vertically disposed cylindrical housing portion 23 which has a base portion 24 that is bolted by means of bolts 24a to the upper surface of the plate 9. Beneath the base portion 24 the plate 9 is provided with a large opening 25, in order to permit vertical movement of the sealing head 26. Above the housing portion 23 is a housing portion 38 which is bolted to portion 23. The sealing head 26 is adjustable by a collar 39 and collars 46, as described in my co-pending application.

The sealing head 26 is actuated by a unit disposed within housing 59, as described in my co-pending application. This housing 59 is bolted to housing portion 38 by a bolt 65, which is connected to lug 66 on member 59. One end of housing 59 is closed by a head 71 and the other end is closed by a head 72. Head 72 carries a sleeve portion 73 in which the piston rod 56 reciprocates. Piston rod 56 is connected to the sealing head 26 in the manner described in my co-pending application. The unit in housing 59 is controlled by a trigger 132 which is engaged by a cap on a container moved into sealing position as described in my co-pending application.

The cap-feeding and applying unit 2 is illustrated best in Figures 3, 4 and 5 to 7, inclusive. This unit comprises a plate 133 which is suitably bolted to the plate 9 over an extension of the opening 25 in the plate 9. This plate 133 has a portion 134 which extends down into the opening 25. The plate 133 is bolted to the plate 9 by means of wing bolts 135 so that it may be readily removed. The plate 133 is provided with a centrally disposed opening 136 which is in alignment with the sealing head 26. This opening 136 is of the proper size to permit the caps, to be applied to the containers, to drop freely therethrough. The plate 133 carries four up-standing posts 137 which are spaced circumferentially around the opening 136. These posts 137 are adapted to receive a stack of the nested caps.

For controlling the feed of the caps downwardly through the opening 136, I provide the following structure. This structure embodies a pair of cap separating wedge members 138. These wedge members 138 are disposed tangentially to the opening 136, as indicated best in Figure 5. They are mounted for axial movement in the plate 133. The outer ends of these members 138 are connected to block members 139 which receive a transversely extending pin 140. This pin 140 is engaged intermediate its ends by a yoke 141, formed on the lower end of a lever 142, which is vertically disposed. The lever 142 is pivoted at 143 between a pair of lugs 144 projecting from the housing portion 23. The upper end of the lever 142 is pivoted at 145 to the outer bifurcated end of a link 146. The inner bifurcated end of the link 146 is pivoted to the outer end of the piston rod 56 which passes through an opening 150 in the housing portion 38. It will be apparent that when the piston rod 56 reciprocates, it will swing the lever 142 about its pivot 143. Consequently, this will move the members 138 axially.

The members 138 are of the shape shown in the drawings, particularly in Figure 4. Each of the members 138 has a flat lower surface 148 formed intermediate its ends. This lower flat surface has a cam shoulder 149 formed thereon. Beneath each of the members 138 is a stop finger 150 which is mounted for axial movement in a

tubular housing 151 at right angles to the member 138. The tubular housing is disposed in a bore 152 extending radially from the peripheral wall of the opening 136. The outer end of the finger 150 is reduced and has a compression spring 153 associated therewith. This spring normally tends to force the finger 150 inwardly towards the center of opening 136. A nut 154 threaded on the outer end of finger 150 and engaging the outer end of housing 151 limits this inward movement. The inner end of the finger 150 is provided with a flattened portion 155 which normally projects inwardly beyond the wall of the opening 136 and upon which the lowermost cap normally rests. The two fingers 150 will be diametrically opposed and will normally prevent downward movement of the caps through the opening 136. It will be noted that they are spaced above the bottom of the opening.

Above the surface 155 a cam shoulder 156 is formed on the finger 150. This cam surface 156 is in engagement with the cam shoulder 149 of the member 138. When the member 138 is moved in the direction of the arrow (Figure 4) the cam shoulder 149, engaging cam surface 156, will force the stop finger 150 outwardly against the force of the spring 153. This will withdraw the finger completely from the opening 136 out of engagement with the lowermost cap and will permit the cap to drop. As soon as member 138 is returned again to the position indicated in Figure 4, the finger 150 will be forced inwardly by the spring 153.

Each of the members 138 also has a flat vertical surface 157 formed thereon intermediate its ends. This surface 157 has a cap-separating wedge portion 158 formed thereon but extending only to the point 159, which is almost the midpoint of the flat surface 157. As shown best in Figure 5, the projecting portion 155 of stop finger 150 is disposed directly adjacent the point 159 where the wedge portion 158 is formed. This wedge portion 158 is provided with a horizontally disposed upper edge 160 which is spaced above the top surface of portion 155 a distance substantially equal to the thickness of a cap. The lower edge 161 of wedge portion 158 is inclined so that the end 159 of portion 158 is pointed. It will thus be apparent that the lowermost cap will normally be supported by the projecting portions 155 of the stop fingers 150. However, when the members 138 are drawn outwardly by movement of the lever 142, this causes the fingers 150 to be moved so that the portions 155 thereof are withdrawn from the opening 136, permitting the lowermost cap to drop from the opening. At the same time that the portions 155 are withdrawn, the pointed ends 159 of the cam portions 158 pass between the lowermost cap and the cap next above. The wedge-shaped cam portions 158 actually serve to force the lowermost cap downwardly. It is desirable to have this positive action rather than to rely upon gravity, because the caps may tend to stick together. The straight upper edges 160 of the portions 158 will support the cap next above and the entire stack during the time fingers 150 are in the withdrawn position. As soon as the lever 142 returns the members 138 to their original positions, the portions 155 will again project into the opening 136 and the lowermost cap will rest thereon, since the wedge portions 158 have been moved from beneath the cap which they were previously supporting. Thus, it will be apparent that each time the piston rod 56 is moved outwardly to

the right (Figure 2) a single cap will drop through the opening 136.

The cap released from the stack will drop downwardly onto a leaf member 162 which is secured to a block portion 163 that is pivoted by the pivot pin 164 to the lower portion of the plate 133. The leaf member 162 extends beneath the opening 136. Also secured to the block 163, is a pair of parallel tracks 165 which extend forwardly towards the sealing head 26. These tracks 165 are spaced apart a proper distance so that they will support the cap 5 released from the stack. Thus, the cap will be supported in an inclined position, as indicated in Figure 3, by the tracks 165 engaging it at diametrically opposed points and by the leaf member 162 engaging the rear edge thereof. Although the members 165 are spaced a distance such that the cap will rest thereon, they are spaced sufficiently to permit the upper end of the container to pass therebetween, it being understood that the cap is slightly greater in diameter than the upper end of the container.

The tracks 165 are normally held in horizontal position by means of a vertically disposed pin 166 which engages a rearward extension 167 on the block 163. This pin 166 is vertically disposed in an extension 168 of the plate 133. It is provided with a small projection 169 which cooperates with a bayonet slot 170 formed in portion 168. With this structure, the pin may be inserted and rotated and will be locked in position so that it will hold the tracks 165 in horizontal position. Above the forward ends of the tracks 165, a leaf member 171 is disposed which is secured to the lower surface of the plate 133 beyond the opening 136. This leaf 171 extends to a point adjacent the sealing head 26 and is provided in order to preclude accidental movement of a cap up between the plate 133, and associated parts, and the member 26.

It will be apparent that all parts of the cap-feeding unit are carried by the plate 133. Consequently, when different sized caps are used, the entire unit may be removed easily and quickly and replaced with a different unit adapted to contain and feed caps of a different size. When removing the cap-feeding unit, it is desirable to remove the pivot 143 to permit the lever 142 to be disengaged from the pin 140. Therefore, the pivot 143 is merely held in position by means of a leaf spring 172, secured to the lever, which carries a pin on its upper end that engages an annular groove in the pivot pin 143 and normally prevents axial movement thereof. If a cap becomes bent or damaged and wedges in the guide-way formed by the tracks 165, the pin 166 may be removed to permit the tracks 165 to swing downwardly into a vertical position so that the damaged cap can be removed.

When the conveyer moves a container beneath the cap-feeding unit 2, the upper end of the container will engage the skirt of the inclined cap disposed in the position indicated in Figure 3. This will move the cap along the tracks 165 with the container. The cap and container will be moved along until they pass beneath the sealing head 26. As described in my co-pending application, sealing of the cap on the container will then be effected.

It will be apparent from the above description that I have provided a cap-feeding and applying unit having a number of advantages. Some of these advantages have been discussed and others will be apparent.

Having thus described my invention, what I claim is:

1. A cap-feeding unit comprising a magazine for supporting a stack of caps of circular outline, said magazine having a cylindrical chamber at the bottom thereof in which the lowermost portion of the stack of caps will be disposed and through which the caps are adapted to pass, means for controlling the feed of the caps through said cylindrical chamber, said means comprising a pair of diametrically opposed fingers mounted for reciprocation in guideways diametrically opposed relative to said chamber and having their inner ends opening into said chamber, said fingers having upper horizontally disposed cap supporting surfaces on their inner ends, springs in said guideways associated with said fingers for normally projecting them toward each other into said chamber so that they will support the lowermost cap in said chamber, a pair of cap separators disposed substantially at right angles to said fingers, said cap separators being disposed for reciprocation in guideways arranged substantially tangentially relative to said chamber and opening into said chamber at their inner edges intermediate their ends, said cap separators having cam portions which engage the fingers upon reciprocation of the separators and withdraw the fingers from said chamber so as to release the lowermost cap, said cap separators having wedge portions which will enter into said chamber during a portion of the reciprocating movement of the separators and will be projected between the lowermost cap and the cap next above so as to force the lowermost cap downwardly and support the cap next above during the time said fingers are withdrawn said wedge portions having upper horizontal cap supporting surfaces disposed at a distance above the cap supporting surfaces of said fingers which is substantially the thickness of a cap so as to engage said cap next above and lower inclined cam surfaces adapted to engage said lowermost caps, the sharp ends of said wedge portions terminating short of the positions of said fingers.

2. A cap-feeding unit comprising a magazine for supporting a stack of caps of circular outline, means for controlling the feed of the caps from the lower end of said magazine, said means comprising a pair of diametrically opposed fingers mounted for reciprocation in guideways diametrically opposed relative to said magazine and having their inner ends opening into said magazine, said fingers having upper horizontally disposed cap supporting surfaces on their inner ends, springs in said guideways associated with said fingers for normally projecting them toward each other into said magazine so that they will support the lowermost cap in said magazine, a pair of cap separators disposed substantially at right angles to said fingers, said cap separators

being disposed for reciprocation in guideways arranged substantially tangentially relative to said magazine and opening into said magazine at their inner edges intermediate their ends, said cap separators having cam portions which engage the fingers upon reciprocation of the separators and withdraw the fingers from said magazine so as to release the lowermost cap, said cap separators having wedge portions which will enter into said magazine during a portion of the reciprocating movement of the separators and will be projected between the lowermost cap and the cap next above so as to force the lowermost cap downwardly and support the cap next above during the time said fingers are withdrawn said wedge portions having upper horizontal cap supporting surfaces disposed at a distance above the cap supporting surfaces of said fingers which is substantially the thickness of a cap so as to engage said cap next above and lower inclined cam surfaces adapted to engage said lowermost caps, the sharp ends of said wedge portions terminating short of the positions of said fingers.

3. A cap feeding unit comprising a magazine for supporting a stack of caps, means for controlling the feed of caps from the lower end of said magazine, said means comprising a pair of opposed fingers mounted for reciprocation in opposed guideways at the lower end of said magazine, said fingers normally projecting from said guideways toward each other into said magazine and having upper horizontally disposed cap supporting surfaces so that they will support the lowermost cap in said magazine, a pair of cap separators disposed substantially at right angles to said fingers, said cap separators being disposed for reciprocation in guideways disposed adjacent opposite edges of said magazine and opening into said magazine at their inner edges intermediate their ends, said cap separators having cam portions which engage the fingers upon reciprocation of the separators and withdraw the fingers from said magazine so as to release the lowermost cap, said cap separators having wedge portions which will enter into said magazine during a portion of the reciprocating movement of the separators and will be projected between the lowermost cap and the cap next above so as to force the lowermost cap downwardly and support the cap next above during the time said fingers are withdrawn, said wedge portions having upper horizontal cap supporting surfaces disposed at a distance above the cap supporting surfaces of said fingers which is substantially the thickness of a cap so as to engage said cap next above and lower inclined cam surfaces adapted to engage said lowermost caps, the sharp ends of said wedge portions terminating short of the positions of said fingers.

HARRY E. STOVER.
